COMBINED SURFACE AND LINE LEVEL

Seymour A. Ostrager, 1188 Grand Concourse,
Bronx, N.Y. 10456

Filed Nov. 6, 1970, Ser. No. 25,855

Term of patent 14 years

Int. Cl. D10—05

U.S. Cl. D52—6

FIG. 1 is a perspective view of a combined surface and line level showing my new design;

FIG. 2 is a top plan view thereof;

FIG. 3 is a side elevational view thereof taken along the line 3—3 in FIG. 2;

FIG. 4 is an end elevational view taken along the line 4—4 in FIG. 3; and

FIG. 5 is a bottom plan view taken along the line 5—5 in FIG. 3.

I claim:

The ornamental design for a combined surface and line level, substantially as shown.
